US00D742583S

(12) **United States Design Patent**
Gettings et al.

(10) **Patent No.:** **US D742,583 S**
(45) **Date of Patent:** **** Nov. 3, 2015**

(54) **NIGHTLIGHT AND AIR SENSOR**

(71) Applicant: **Leeo, Inc.**, Palo Alto, CA (US)

(72) Inventors: **Adam M. Gettings**, Red Wing, MN (US); **Victoria Slaker**, San Francisco, CA (US); **Bengt Brummer**, San Francisco, CA (US)

(73) Assignee: **Leeo, Inc.**, Palo Alto, CA (US)

(**) Term: **14 Years**

(21) Appl. No.: **29/483,655**

(22) Filed: **Feb. 28, 2014**

(51) LOC (10) Cl. **26-99**

(52) U.S. Cl.

USPC **D26/152**; D10/52; D10/53

(57) **CLAIM**

The ornamental design for a nightlight and air sensor, as shown and described.

DESCRIPTION

FIG. 1 is a front side perspective view of a nightlight and air sensor;

FIG. 2 is a bottom view thereof;

FIG. 3 is a left side elevation view thereof;

FIG. 4 is a rear elevation view thereof;

FIG. 5 is a front bottom perspective view thereof;

FIG. 6 is a right side elevation view thereof;

FIG. 7 is a front elevation view thereof;

FIG. 8 is a top elevation view thereof;

FIG. 9 is a rear bottom perspective view thereof;

FIG. 10 is a rear top perspective view thereof; and,

FIG. 11 is a rear bottom perspective view thereof.

All features illustrated in phantom line are expressly disclaimed and form no part of the claimed design.

1 Claim, 11 Drawing Sheets
